UNITED STATES PATENT OFFICE.

GEORGE W. MILLER, OF WATERLOO, IOWA.

WINDMILL.

SPECIFICATION forming part of Letters Patent No. 256,154, dated April 11, 1882.

Application filed September 28, 1881. (Model.)

To all whom it may concern:

Be it known that I, GEORGE W. MILLER, a citizen of the United States, residing at Waterloo, in the county of Black Hawk and State 5 of Iowa, have invented certain new and useful Improvements in Windmills; and I do hereby declare that the following is a full, clear, and exact description of the same, reference being had to the annexed drawings, making a 10 part of this specification, and to the letters and figures of reference marked thereon.

Figure 1 of the drawings is a side elevation of my invention; and Fig. 2, a detail view, in perspective, of a portion of the operating 15 mechanism.

The present invention relates to certain novel improvements in windmills; and it consists in the several details of construction, as will be hereinafter described, and subsequently pointed 20 out in the claim.

In the accompanying drawings, A is the wind-wheel, and B the rudder or vane, both of which may be of metal or wood and of the usual construction.

25 The hollow standard C has adjustably connected to it a bracket, D, the latter having eyes a, through which passes the hollow standard, and to which is rigidly secured the shaft b of the rudder or vane, said bracket being held 30 at the required position on the standard by a set-screw, c.

The turn-table E is connected to the standard C in any suitable manner that will admit of its turning horizontally to either the right 35 or left, so as to bring the wheel A into the wind or action and regulate the same during high winds or storms. The upper portion of this turn-table E forms a bearing for the shaft of the wheel A, and to the inner end of the shaft 40 is keyed a disk, d. To this disk is eccentrically connected one end of a pitman, e, the other end being suitably connected to an operating-rod, f, which passes down through the hollow standard C, thereby giving to the rod 45 f a vertically-reciprocating motion as the wind-wheel revolves. A spring-brake, g, passes around a groove in the periphery of the disk d, and is connected to a lever, h, the latter being pivoted to the turn-table E, so that the

50 brake g is tightened around the periphery of the disk by the action of the lever when it is desired to bring the wind-wheel to rest and to prevent the wheel from coming to a sudden

stop, which might break it or cause strain upon the operating parts. This danger is prevented 55 by the employment of the brake and pivoted lever for operating it, which brings the wheel to a gradual and easy stop.

The upper end of the rod f passes through a head, F, suitably connected to the end of 60 the hollow standard C, said head having a pulley, i, over which passes a cord or rope, k. One end of this cord or rope is connected to a pivoted lever, having secured thereon an adjustable weight, l, while the other end of the 65 cord or rope passes down through the hollow standard C in convenient reach of the attendant, who draws down upon it when it is desired to stop the wheel A, as will be presently described.

To the pivotal end of the lever G is rigidly connected a segmental rack, H, the teeth of which engage with those of a similarly-formed rack, I, said rack being connected to or forming part of the turn-table E. As the cord or 75 rope k is pulled down the lever G will be raised, and the teeth of the rack G engaging with those of the rack I, it will bring the turn-table E around in the direction so as to cause the foot m to come in contact with the lever h and 80 press it down, which will cause the brake g to be drawn down tightly around the periphery of the disk d, thereby gradually stopping the wind-wheel without danger of injury to the 85 operating parts.

It should be noticed that the lever G is pivoted to the bracket D, and the weight thereon is adjustable by a suitable set-screw, as is common in this class of windmill, and therefore needs no further description.

Having now fully described my invention, what I claim as new, and desire to secure by Letters Patent, is—

The turn-table E, supporting wheel A, disk d, brake g, pivoted lever h, and the rack I, in 95 combination with the bracket D, pivoted lever G, rack H, and cord or rope k, substantially as and for the purpose set forth.

In testimony that I claim the above I have hereunto subscribed my name in the presence 100 of two witnesses.

GEORGE W. MILLER.
